UNITED STATES PATENT OFFICE.

JESSE A. LEWIS AND LESLIE L. REW, OF NIAGARA FALLS, NEW YORK.

RAIL JOINT.

1,419,973.

Specification of Letters Patent. Patented June 20, 1922.

Application filed July 18, 1921. Serial No. 485,538.

To all whom it may concern:

Be it known that we, JESSE A. LEWIS and LESLIE L. REW, citizens of the United States, residing at Niagara Falls, in the county of 5 Niagara and State of New York, have invented certain new and useful Improvements in Rail Joints, of which the following is a specification.

This invention relates to improvements 10 in rail joints.

The primary object of the invention is the provision of an improved connection for rail joints, in which the rails are yieldably maintained in position with respect to 15 each other, to form a roadway.

A further object of the invention is the provision of a secure and durable splice connection for rail joints, which effects the connection between adjacent rails without 20 the use of bolts or screws.

The improved rail joint specifically embodies a pair of spliced plates having resilient means for cooperation therewith, to yieldably maintain rails in proper trackway 25 relation.

Other objects and advantages will be apparent during the following detailed description.

In the accompanying drawings, forming 30 a part of this specification, and in which similar reference characters designate corresponding parts throughout the several views.

Figure 1 is a perspective view of the improved connecting joint for rails.

Figure 2 is a cross sectional view taken on the line 2-2 of Figure 3.

Figure 3 is a longitudinal sectional view taken on the line 3-3 of Figure 2.

Figure 4 is a perspective view showing several details of the improved rail joint, and their cooperating parts.

Figure 5 is a perspective view of a clamp used in connection with the improved rail joint.

In the drawing, wherein for the purpose of illustration is shown the preferred embodiment of this invention; the letters A and B designate rails in alignment for use 50 upon a trackway. Splice plates C are used in connection with the abutting ends of the rails A and B for properly positioning the rails A and B with respect to each other; clamps D, and springs E cooperat- 55 ing with the splice plates C to provide a proper rail connection.

The rails are, of course, of any preferred construction, depending upon the use for which the trackway is provided. In most instances, the rails A and B will be the ordinary standard track rails provided with a foot 10, a wheel engaging head 11; said foot and head being connected by the ordinary web construction 12. For use in connection with the improved rail joints, 60 the rails A and B are each provided with a slot 13, extending longitudinally of the web 12, and positioned adjacent the ends of the rail a predetermined distance therefrom.

The splice plates C are simple in construction, a pair of these splice plates C being used for each rail joint. The plates C are each provided with a pair of slots 15 and 16, of the same length as the slot 65 13, and having the end edges 17 and 18 of each of the slots 15 and 16 rounded from the inside surface 19 to the outside surface 20 of the splice plates C, to provide a proper riding surface for the clamps D. Substan- 70 75 tially rectangular lugs 21 and 22 are provided upon the exterior face 20 of each of the splice plates C, said lugs 21 and 22 being positioned adjacent the rounded edges 17 of slots 15 and 16. An intermediate 75 80 projecting lug 23 is provided between the rounded edges 18 of the slots 15 and 16. It is preferred, that the top surfaces 24 of each of the projecting lugs 21, 22 and 23 lie in the same plane defined by the bottom sur- 85 90 face 25 of each of the slots 15 and 16, and which likewise lie in a common plane.

The clamps D are divided into the relatively long clamp members 28, of which two are provided for each rail joint, and adapted 95 for use in connection with the remote rounded edges 17 of the slots 15 and 16; and the relatively short clamp means 29 of which two are provided for use upon the rounded edges 18 of the slots 15 and 16; said clamps 100 28 being positioned intermediate the clamps 28.

The clamps 28 are substantially U-shaped in formation, each being provided with legs 30 and 31, integrally connected by a bight 105 portion 32. The space between the legs 30 and 31 is just sufficient to comfortably receive the thickness of the two spliced plates C and a web 12 of a rail. The bottom of the pocket 34, defined between the legs 30 110 and 31, is rounded to accommodate the rounded surfaces 17 as provided in the slots

15 and 16. A spring retaining projection 35 is preferably formed exteriorly upon the bight portion 32 of each of the clamps 28, and extending oppositely from the legs 30
5 and 31. This structure, however, need not be strictly adhered to, since depressions or recesses may be provided in the bight portions 32 for the purpose of receiving the springs E, to be specifically described herein-
10 after.

10 after. The clamps 29, are substantially U-shaped in formation, and altogether similar to the clamps 28. The legs 36 and 37 of each of the clamps 29, are, however, shorter than the legs 15 of the clamps 28. The legs 36 and 37 of each clamp 29 are connected integrally by a bight portion 38, and spaced the same distance as the legs 30 and 31, of the clamps 28. The bottom surface of the pocket or recess 39, 20 provided by the clamp 29, is rounded, to accommodate the rounded edges 18 of the splice plate slots 15 and 16. Spring retaining projections 40 are provided upon the bight portions 38 of each of the clamps 29, 25 extending oppositely thereon from the legs of these clamps, and adapted for the purpose of receiving and retaining the springs E. to be subsequently set forth.

The springs E are preferably of the spiral type, and adapted for use under compression, between a clamp 28 and a clamp 29, each of the springs E, of which two are provided for a rail joint, engaging a spring projection 35, and a spring projection 40 of the clamps 28 and 29 respectively.

35 the clamps 28 and 29 respectively.

In assembling, the rails A and B are of course positioned to form a trackway in the ordinary manner. When so positioned, the slots 13 of the rails A and B will be spaced 40 a predetermined distance from each other, for cooperation with the splice plates C. The splice plates C are next positioned upon opposite sides of the webs 12 of the rails A and B, and in such relation that the slots 15 45 and 16 of the splice plates C are in alignment with each other, and with the slots 13 of the rails A and B. The clamps 28 and 29 are next positioned in the manner above set forth, namely, with clamps 28 adjacent the 50 rounded edges 17 of the slots 15 and 16, and the clamps 29 intermediate the clamps 28. Both sets of clamps 28 and 29 are positioned through the slots 15 and 16, with the portions 32 and 38 extending through the slots 55 in the splice plates and webs, and having the legs 30 and 31 of the clamps 28, and legs 36 and 37 of clamps 29 lying exteriorly upon the outer surfaces 20 of the splice plates C.

In arranging the clamps D, a clamp 28 and a clamp 29 are provided for each slot 15 and 16 of the splice plates C. The spring retaining projections 35 and 40 of the clamps 28 and 29 extend in axial alignment within the slots 13 of the rails A and B, and in this position are adapted to receive the

springs E under powerful compression, whereby the bight portions 32 and 38 of the clamps 28 and 29 are forced into firm engagement with opposite ends of the slots in the rail webs 12, and the slots 15 and 16 of 70 the splice plates C. In their assembled positions, the clamps 28 have their legs 30 and 31 resting upon the guiding surfaces 24 of the projecting lugs 21 and 22; the legs 36 and 37 of the intermediate clamps 29 resting upon the intermediate lugs 23 on the splice plates C.

splice plates. From the foregoing, it can be seen that the springs E being under powerful compression, will force the clamps D into engagement with the extreme end surfaces 45 and 46 of the slots 13, in rails A and B, and thus maintain the rails A and B in a pre-determined relation with respect to each other. By reason of the resiliency of the springs E, expansion and contraction of the rails A and B is provided for under all conditions. Thus the flexible rail joint structure will solve a problem heretofore experienced in extreme temperatures where expansion in the rails A and B becomes a serious problem. As now provided in standard practice, the American Society of Civil Engineers provide the splice plates for a rail joint connection having elliptical holes 95 therein for receiving the cross bolts for clamping them to the web of a rail, and in addition provide a considerable space, namely, one eighth of an inch between the facing ends of the rails A and B. The 100 above described flexible rail joint, by reason of its nature in itself provides for expansion and contraction in the rails A and B.

If there is a tendency of the rails A and B to pull apart, the end surfaces 45 of the slots 13 in webs 12, will engage the inner surfaces of the pockets 39, and force the clamps 29 apart to further compress the springs E. However, due to powerful compression of the springs E, the rails A will be kept in alignment. Very little wear will result upon any portion of the improved rail joint structure, and the same may be maintained for an indefinite length of time, without attention. 115

without departing from the spirit of the invention or the scope of the claims. 120

We claim:

1. In a device of the above described class, the combination of rails, splice plates for disposition over the facing ends of said rails, and resilient means connecting said splice plates to said rails to permit longitudinal movement of said rails with respect to each other. 125

2. In a device of the above described class, the combinations of rails, splice plates, 130

clamps for connecting said splice plates to said rails, and spring means engaging said clamps for yieldably maintaining said rails for longitudinal expansion and contraction.

5 3. In a device of the above described class, the combination with a pair of rails having longitudinal slots in the web portion thereof, and spring means for engaging through said slots for connecting said rails together 10 for flexible movement with respect to each other.

4. In a device of the above described class, the combination of rails having slots in the web portion thereof, splice plates having 15 slots therein for alignment with the slots in said rail webs, clamps through slots in said splice plates and said rail webs, and

spring means engaging said clamps for maintaining the rails in longitudinal alignment.

5. In a device of the above described class, the combination of rail members having longitudinal slots in the web portions thereof, a pair of splice plates for disposition upon the sides of said web, said splice plates 25 having a pair of slots therein for alignment with the slots in said rail webs, a pair of clamps engaging through aligning slots in the splice plates and rail webs, and spring means for engaging said clamps to maintain 30 said rail members in longitudinal alignment.

JESSE A. LEWIS.
